UNITED STATES PATENT OFFICE.

JOSEPH B. STRAUSS, OF CHICAGO, ILLINOIS.

ELEVATED RAILWAY.

Application filed January 19, 1917. Serial No. 143,219.

To all whom it may concern:

Be it known that I, JOSEPH B. STRAUSS, a citizen of the United States, residing at Chicago, in the county of Cook and State 5 of Illinois, have invented a certain new and useful Improvement in Elevated Railways, of which the following is a specification.

This invention relates to elevated railways and has for its object to provide a new 10 and improved device of this description which shall be comparatively cheap to construct, efficient and safe in operation. The invention is illustrated in the accompanying drawings, wherein—

Fig. 1 is a side view of a portion of the elevated structure.

Fig. 2 is an enlarged sectional view taken on the line 2—2 of Fig. 1.

Fig. 3 is an enlarged detailed view of the 20 movable supporting parts for a section of the rail.

Fig. 4 is a plan view showing the cross-over from one track to the other.

Fig. 5 is a sectional view taken on line 25 5—5 of Fig. 4.

Fig. 6 is a sectional view taken on line 6—6 of Fig. 5.

Fig. 7 is a vertical sectional view showing a modified form of the elevated structure.

Like numerals refer to like parts throughout the several figures.

Referring now to the drawings, I have shown an elevated structure made up of a series of central posts or supports 1 spaced 35 at suitable intervals. Mounted upon these supports are a series of longitudinal main carrying members 2, 3 and 4. These main carrying members may be trusses or beams or any other construction (see Figs. 1 and 2). In the construction shown, there is 40 a central main carrying member and two side main carrying members, one on each side of the central member. The central member is supported upon the central support and the side members are connected therewith in any desired manner so as to 45 also be supported thereby.

In Fig. 2, there is shown a structure for carrying two tracks. A series of cross-over supports 5 are suitably spaced apart and are supported upon the central supports and the beams 6, said beams being supported upon the braces 7 connected with the central supports. The cross supports are can- 50 tilevered beyond the beams and the inner

rails 8 are carried on the cantilevered ends, there being preferably longitudinal sleepers 9 between the rails and the cross supports. The outer rails 10 are supported on the cross supports 11 carried by the outer carrying members 3 and 4. These cross supports preferably rest upon the lower members 12 of the main carrying members 3 and 4 and are cantilevered beyond said members, the rails 10 being supported upon the cantilevered 60 ends, sleepers 9 being interposed between the rails and the cross supports. The outer ends of the cross supports 11 are connected by the inclined members 13 with the upper portion of the members 3 and 4. It will 65 thus be seen that there is an open space between the rails 8 and 10 for the connection between the cars 14 and the trucks 15 which run upon said rails. The upper portion of the cars preferably project into the structure, as shown in Fig. 2, and is connected to the truck by connection 15^a. Each car is preferably provided with a motor 16 which may be mounted upon the truck, as 70 shown. There is also a safety device 17 connected with the car and having members 18 which project over the rails but which are ordinarily out of contact therewith, so that if the normal connection between the car and the truck fails, this safety 75 device will engage the rails and keep the car from falling. There is preferably arranged a platform 19 placed on a level with the bottom of the door of the car and extending between the two cars so that if anything happens to cause the cars to stop between stations, passengers can get out on this platform and walk to the next station. This platform is supported upon a longitudinal support 20 which also acts as a 80 hand rail and divides the platform into two sections, one for each track. This platform is also preferably provided on each side with engaging devices 21 which engage the sides of the cars so as to properly guide 85 the cars and prevent them from swinging. There are suitable platforms 22 and 23 at the stations and on the outside of the cars 14, and these platforms and the platform between the cars are arranged so that the 90 passengers may be loaded into each car from one platform and unloaded on to the other platform, there being a platform on each side of each car. These platforms are 95 preferably on a level or flush with the car 100 105 110

floor. Some means is provided to permit the trucks of the cars to be easily placed in position on the track or removed therefrom. As shown, this result is secured by arranging some of the cross supports 11 at suitable intervals so that they can be moved laterally, as shown in Fig. 3. In this figure the pieces 13 are pivoted at 13^a to the cross support and at 13^b to the main carrying member, and there are rollers 11^a arranged to engage the flanges of the cross supports so that they may be moved laterally about the position shown in dotted lines in Fig. 3, thus moving the rail 10 so as to increase the space between the rails 10 and 8 a sufficient amount to permit the truck to be moved or inserted. In Fig. 7 I have shown a modified construction where there is a space to be used for three tracks. This construction may be similar to that shown in Fig. 2 with the addition at the top of a series of vertical members 24 which carry cantilever cross supports 25 carrying the rails 26 for the third track. The vertical members are connected together at the top by the connecting piece 27. I also prefer to provide guides 28 on all the structures above the wheels to act as guides for the flanges of the wheels, the flanges thereby being guided at the bottom by the rails 26 and at the top by the guides 28. Suitable cross-overs are arranged at suitable intervals so that a car may be transferred from one track to the other. One form of this cross-over is shown in Figs. 4, 5 and 6. In this construction a switch track is provided extending from the track of one side to the track on the other and comprising rails 30 and 31 preferably fixed. A bridging member 32 is provided pivoted at one end on the pivot 33 and having mounted upon it the two rail sections 34 and 35 (see Figs. 5 and 6). The bridging member 32 has connected therewith an arm 36 provided with the cross piece 37 carrying the rollers 38, which rollers engage the flange of an arc-shaped support 39. It will thus be seen that the ends of the rail sections 34 and 35 may be moved by moving the arm 36. By moving this arm to one position the section 35 connects with the rail 30 and with the rail section 40 (see Fig. 4) so that the truck may be transferred from the track at one side to the track at the other side. The rail 31 connects with the rail 8 and by moving the arm 36 in the other direction the rail section 34 is moved to connect with the section 41. The sections 40 and 41 will also move and when in this position the section 41 is moved up against the section 8 so that there is a clear through track, the cross-over being then disconnected. It will be seen that by means of this construction the sections of the track of the cross-over may be moved to make the proper connec-

tion and at the same time there is an open space for the passage of the car hanger so that the car may be easily moved from one track to the other.

In the construction illustrated the motors 70 are electric motors and there are conductors 42 extending along the structure, the motors being connected in circuit with the sliding shoes 43 slidably engaging the conductors.

In order to deaden the sound, sound-deadening material is placed between the cross supports which carry the rails and the members carrying said cross supports, shown at 12^a, Fig. 3.

I claim:

1. A railway structure comprising a series of central supports, a series of central main carrying members connecting said central supports and bracing them, a side main carrying member on each side of said central member, cross members connecting said side main carrying members with said supports, rails supported between the main carrying members, cross supports at intervals under said rails, some of said cross supports projecting through the side main carrying members, and connecting members connecting the outer ends of said cross supports with said main carrying members. 80

2. A railway structure comprising a series of central supports, a series of central main carrying members connecting said central supports and bracing them, a side main carrying member on each side of said central member, cross members connecting said side main carrying members with said supports, rails supported between the main carrying members, cross supports at intervals under said rails, some of said cross supports projecting through the side main carrying members, means for transferring the stresses, due to the load on the rails, from the inside of said side main carrying members to the outside thereof and then back to said main carrying members. 95

3. A railway structure comprising a series of central supports, three main carrying members, one central with said supports, cantilevered members connecting with and supporting the other two main members, 100 cross supports projecting laterally on each side of the central main members toward the outer main members, cross supports connected with the outer main members and projecting toward the central main member 105 and means connected with the ends of said cross members for carrying the rails so as to leave an opening space between said rails. 110

4. A railway structure comprising a series of central supports, three main carrying members, one central with said supports, cantilevered members connecting with and supporting the other two main members, cross supports projecting laterally on each side of the central main members toward 115 120 125 130

- the outer main members, cross supports connected with the outer main members and projecting toward the central main member and means connected with the ends of said 5 cross members for carrying the rails so as to leave an open space between said rails, sound-deadening material located intermediate said cross supports and the members carrying them.
- 10 5. A railway structure comprising a plurality of main carrying members two of which are outer members and another centrally therebetween, tracks for cars located between the central member and the outer 15 members, supports for said main carrying members, cars mounted to travel along said tracks and longitudinal guides for said cars located below the central main member.
6. A railway structure comprising a 20 plurality of main carrying members two of which are outer members and another centrally therebetween, tracks for cars located between the central member and the outer members, supports for said main carrying members, cars mounted to travel along 25 said tracks and longitudinal guides for said cars located below the central main member, supports for said guides and a foot-walk on said guides.
- 30 7. A railway structure comprising three longitudinal main carrying members substantially parallel to each other, supports for one of said main carrying members at intervals, the other main carrying members being connected with said supports so as to be supported thereby, two open ways between said main carrying members, rails within said open ways and supporting means for supporting said rails in position.
- 40 8. A railway structure comprising three longitudinal main carrying members, tracks for cars between the outer members and the central member, and single supporting posts in the plane of the central member and 45 located at intervals therealong.
9. A railway structure comprising longitudinal main carrying members, two outer members and a central member, an open way between said main carrying members, 50 rails mounted within said open way and eccentric with respect to said main carrying members and means for transmitting the load on the rails of the outer carrying members, to the central carrying member and 55 supports for said central carrying member.
10. An elevated structure comprising longitudinal main carrying members, an open space between said main carrying members, cross supports having their ends projecting part way across said open space, 60 rails mounted upon said cross supports, some of said cross supports movably supported in position so that they may be moved to move the rail to increase the distance between
- the rails of the track to permit the wheels 65 of the car to be disconnected from the track.
11. An elevated structure comprising longitudinal main carrying members with an open space between them, rails located in said open space to form a track and supported by said main carrying members, and means at intervals along the track for moving one of the rails laterally to increase 70 the distance between the rails and to permit the wheels of the car to be lowered between 75 said rails.
12. An elevated structure comprising two tracks each comprising two sets of rails, trucks mounted on said tracks, cars suspended from said trucks, the roof of each 80 car formed by inclined meeting sections the portion of the car at the point where said sections meet projecting into the space between said rails.
13. An elevated railway comprising three 85 pairs of rails, cantilevered cross supports carrying said rails, main carrying members carrying said cross supports, two pairs of said rails located below the tops of said main carrying members, and one pair of said 90 rails located above the tops of said main carrying members.
14. An elevated railway comprising three pairs of rails, an open space between each 95 pair of rails, trucks on each pair of rails, cars connected to said trucks, the connection between the cars and the trucks passing between the rails, one pair of rails being located in a horizontal plane above the other two pairs of rails.
15. An elevated railway comprising two 100 overhead tracks, trucks mounted on said tracks, cars suspended upon said trucks, and located below said tracks, loading and unloading platforms below said tracks and flush with the car floor, one of said platforms located between the cars of the two tracks and supported by the same support that supports said tracks, the other platforms located at the outer sides of said cars.
16. An elevated railway comprising three 105 parallel platforms separated by two open spaces for the passage of the cars, main carrying members above said platforms, one of said platforms supported by said main 110 carrying members, overhead tracks supported by said main carrying members above said platforms, trucks mounted on said tracks and connections between said trucks and said cars, said cars located below 115 said tracks.
- In testimony whereof, I affix my signature in the presence of two witnesses this 17th day of January, 1917.
